NEW YORK

THERMOSTAT SWITCH

Application filed May 7, 1930. Serial No. 450,344.

Our invention relates to electric switches. The object of our invention is to provide an electric switch and thermostat construction in which are embodied automatic means for regulating the timing of the action of the switch, and manually operated means for regulating the timing action of the switch.

A further object is to provide a construction in which the contacts are caused to slide in contact with each other to prevent their sticking together at the time of breaking the circuit. A further object is to provide means by which the contacts are held together with increased pressure just prior to the breaking of the circuit.

A further object is to provide a switch mechanism which will not strain the thermostat element in the act of operating the switch, and which will permit a wide gap between the contact points to prevent arcing when the circuit is broken.

Referring to the drawing which forms a part of this specification:

Fig. 1 is a plan view of a switch mechanism of the single pole type in which our invention is shown.

Fig. 2 is a side elevational view of the construction shown in Fig. 1, the base plate being shown in section.

Fig. 3 is a fragmental view showing the means for holding the thermostat element and manually adjusting the same, the view being taken on line 3-3 of Fig. 1.

Fig. 4 is a view taken on line 4-4 of Fig. 1.

Fig. 5 is an illustrational view, taken on line 5-5 of Fig. 1.

Fig. 6 is a plan view showing a double pole switch and a modified form of thermostat element.

Fig. 7 is a longitudinal sectional view of the lever shown in Fig. 6 on line 7-7 thereof.

Fig. 8 is a cross sectional view of the lever shown in Fig. 7 taken on line 8-8 thereof.

Fig. 9 is a cross sectional view of the lever, taken on line 9-9 of Fig. 7.

Fig. 10 indicates a base-plate of insulating material, on which is mounted the switch mechanism. It is provided with a circular hole

11 in which is fitted a metal plug 12 on the top of which is carried a small pin 13 located near its periphery as shown.

This plug is connected to a crank 14 having an upwardly extending handle 15 located adjacent one edge of the base-plate as illustrated in Figures 1, and 6.

A swivel-block 16 formed substantially as shown, is held on the base-plate by a screw 17, which extends thru the base-plate into the boss 16' of the block to hold it in movable relation with the base-plate.

The block 16 is provided with a longitudinally extending V-shaped slot 18 in the construction shown in Fig. 1, which terminates in a slot having parallel walls, and one end of a bi-metallic thermostat element 20 is supported between said walls by a cross-pin 19 in such a manner as will permit the free end of the thermostat to swing upwardly thereon as illustrated in dotted lines in Fig. 3.

21 indicates a terminal for a plug connection, which is carried by a strip of conduction metal 22 held to the base-plate by a screw 23. The strip 23' is bent upwardly at 75 one end to form a bracket 24 on which is mounted a contact point 25. 26 indicates a terminal which is carried by a strip 27 which is secured to the base-plate by screws 28.

29 indicates a screw which extends thru a hole formed in the lever 30 near one end thereof, the hole being countersunk on both sides, and of larger diameter than the screw, to permit the lever to tilt a limited distance on the spherical surface 31 of a washer 32 thru which the screw extends into a thimble 33 fixed in the base-plate.

The end of the lever adjacent its support may be formed on its upper side, with curved surfaces 34 as illustrated in Fig. 5 or Fig. 8 (shown on an enlarged scale).

In Figs. 1 and 2, we have illustrated the bar 30 as a cast metal bar, and in Figs. 6, 7, and 9, as a sheet metal stamping. It may be made in any way desired but is lighter in weight when made of stamped metal and costs less.

The end of the lever 30 adjacent the block 16 is provided with a contact point 35 adapted to abut the contact point 25 as illustrated. 100

A helical spring 36 is connected to the lever adjacent the contact point 35 and its opposite end is connected to the free end of the thermostat 20 by a screw 37 which extends thru a loop formed in the end of the thermostat and carries a clip 38 to which the end of the spring is attached as illustrated. In the construction shown in Fig. 7, a lip 39 is formed integral with the lever in the stamping operation, and a loop is formed in the end of the spring which is slipped under the lip to hold it in place, instead of using a clip 39' as shown in Fig. 2. The lower end of the screw 37 normally extends below the normal level 15 of the surfaces 34 as indicated in Fig. 5.

In Fig. 6, another circuit may be closed immediately after the circuit thru contact points 25 and 35 is broken, by the contact points 40 and 41 being brought together, as 20 will be readily understood.

The bracket 42 serves as a stop for the movement of the lever in Fig. 1, and also carries the contact point 40 when constructed as shown in Fig. 6. 43 and 44 indicate electrical resistance heaters.

The operation of the device is substantially the same in both of the constructions shown, the snap action at the break of the circuit being obtained in both movements of 30 the lever 30.

Assuming the terminals 21 and 26 to be coupled in circuit with a source of supply, the current will flow thru the heater 43, strip 23', contacts 25 and 35 to the lever 30 and strip 27 to the terminal 26, thus energizing the heater 43 which is located adjacent the thermostat 20.

The heat generated by the heater 43 causes the thermostat to bend in the usual manner, 40 and carry the lower end of the screw 37 against the adjacent surface 34 of the lever 30, causing a retardation of the movement of the thermostat in its travel, and holding the contact points 25 and 35 more firmly together. Now if the thermostat is held rigidly in the block 16 in such a manner as to prevent the free end from rising, the lever 30 will be forced to tilt on its fulcrum at 31, and the contact point 35 will be forced to slide upwardly in contact with the contact point 25 in a sliding action, which will prevent any sticking between said points, and when the screw has passed over the surface 34, the spring 36 will act to instantly break the circuit thru the heater 43 and close the circuit thru the heater 44 as will be readily understood.

Now we will assume that both the lever 30 and thermostat 20 are free to tilt; the lever 60 will not tilt so far as before, but will tilt far enough to cause the contact to slide a limited distance, and thus prevent sticking, as before explained.

It is obvious that the lever 30 may be so mounted that it will not tilt, and the switch

may be so constructed if desired; the lifting of the end of the thermostat in passing over the surface 34 against the tension of the spring 36 being sufficient to cause the retardation of the movement of the thermostat, 70 as will be readily understood.

The timing action of the switch may be further controlled by swinging the block 16 by moving the handle 15 and crank 14, thus causing the pin 13 to swing the block to the desired position and causing the thermostat's free end to normally rest nearer to the lever, or further therefrom.

A further means for timing the action is by the use of the block 16, which absorbs heat 80 from the thermostat for a period of time, thus causing a delay in the action of the switch. This block may be made in different sizes, depending on the service required. For illustration; if the heater and switch mechanism is to be used in a coffee percolator, the switch mechanism may be set to operate in 15 or 20 minutes before the thermostat will be heated to a sufficient degree to break the circuit, as will be readily understood.

It is obvious that the heater may be left out of the circuit and an electric motor or other device substituted therefore and located at a distance from the switch, and the switch energized from another source of heat, located 95 adjacent said thermostat.

There is practically no mechanical strain on the thermostat in operating the lever 30, due to the alignment of the spring and thermostat being substantially the same, and therefore the strain is not at an angle sufficient to bend the thermostat or retard its movement.

The mechanism is simple and dependable 105 and low in cost of construction.

Having thus described our invention, we claim as new:

1. A switch of the character described, comprising a base-plate, a thermostat having a normally straight portion one end of which is free to move, a lever having its fulcrum near one end thereof and carrying a contact-point at its opposite end, a spring connected at one end with the free end of the thermostat, and its other end connected with the opposite end of the lever adjacent said contact-point; the ends of said lever being movable laterally to break the circuit and said thermostat being movable into engagement with the lever to move the same upwardly whereby one contact slides relative to the other contact to prevent the contact points from sticking together.

2. A switch comprising a base-plate, a contact-point supported thereon, a lever mounted on the base-plate in tiltable relation thereto having its fulcrum near one end thereof and carrying a contact-point at its opposite end movable in sliding relation to 130

said contact-point mounted on the base-plate, and a thermostat adapted to contact an end of said lever and tilt the same to cause a sliding movement between the contact-points in 5 the act of breaking the circuit.

3. A switch comprising a base-plate, a lever mounted thereon having a contact point adjacent one end thereof, a contact-point supported by said base-plate, a thermostat 10 having means adapted to contact with the short end of said lever and cause said contact-points to press together with increasing pressure just prior to breaking the circuit there-thru.

15 4. As stated in claim 3; said lever being so mounted as to permit movement laterally and upwardly.

5. A switch comprising a base-plate, a lever mounted thereon having a contact-point 20 adjacent one end thereof and having its opposite end formed with a curved surface, a contact-point supported by said base-plate, a thermostat having means carried by the free end thereof for contacting the curved surface 25 of said lever in the act of breaking the circuit thru said contact points.

6. As stated in claim 1; said spring and thermostat extending in parallel relation to prevent excessive strain on said thermostat.

30 7. A switch comprising a base-plate, a contact-point supported thereon, a lever mounted on the base-plate in tilttable relation thereto having its fulcrum near one end thereof and carrying a contact-point at its opposite end 35 movable in sliding relation to said contact-point mounted on the base-plate, a thermostat adapted to contact an end of said lever and tilt the same to cause a sliding movement between the contact points in the act of breaking 40 the circuit, and a spring connected with the lever adjacent the contact-point thereon and with the thermostat adjacent its free end, said spring and thermostat extending substantially parallel to each other.

45 8. As stated in claim 5; a metal block connected in heat conducting relation with said thermostat, and means for adjusting the position of said block to govern the timing action of the switch.

50 In testimony whereof I have affixed my signature.

ALBERT E. GRANT.
